(57) **CLAIM**

The ornamental design for an extraction vial, as shown and described.

DESCRIPTION

FIG. 1 is a perspective view of an extraction vial; FIG. 2 is a first side view of the extraction vial shown in FIG. 1; FIG. 3 is a second side view of the extraction vial shown in FIG. 1; FIG. 4 is a third side view of the extraction vial shown in FIG. 1; FIG. 5 is a fourth side view of the extraction vial shown in FIG. 1; FIG. 6 is a bottom view of the extraction vial shown in FIG. 1; and, FIG. 7 is a top view of the extraction vial shown in FIG. 1. The broken lines immediately adjacent the shaded areas represent the bounds of the claim, and all other broken lines are for illustrative purposes only. None of the broken lines form a part of the claimed design.
